ABSTRACT OF THE DISCLOSURE

The invention provides a method of alleviating inflammation, edema and/or pain in a mammal by administering to said mammal by the topical route gallic acid or an alkyl ester of gallic acid, the alkyl moiety of said ester having 1 to 8 carbon atoms.

This invention relates to the use of gallic acid and its alkyl esters in the topical treatment of inflammation, edema and pain in mammals including humans.

The compositions can contain other ingredients known to have anti-inflammatory, anti-edema and analgesic activities; examples of such ingredients are salicylates and steroids, e.g. hydrocortisone and fluocinolone.

5 A suitable compositions in one comprising propyl gallate in an optimal concentration of 2-10% w/v. in an oily base such as that used for Ointment of Phenol BP 1948; NF 1952. Such a composition should be protected from light during storage. It is particularly useful in the treatment of sunburn.

The following example illustrates the method of the invention.

EXAMPLE

15 Propyl gallate was tested as a local anti-inflammatory agent and compared with hydrocortisone in the rat using the method of Tonelli, Thibault and Ringler, Endocrinology, 1965, 77, 625-634. It was found that propyl gallate had a significant anti-inflammatory activity having a potency of 0.03 relative to hydrocortisone; it did not, however, have the undesirable side-effects of the latter. The results are shown in the Table I below.

TABLE I.—COMPARISON OF THE TOPICAL ANTIINFLAMMATORY EFFECTS OF PROPYL GALLATE AND HYDROCORTISONE

Compound	Concen- tration, mg./ml.	Ear weight, mg.	Increase* in ear weight, mg.	Percent inhibition of ear weight increase	Relative potency (95% confidence limits)
Propyl gallate	1	159±27	87.1±27.1	12.0±27.3	-----
Do	3.16	153±29	80.5±29.0	18.7±29.3	-----
Do	10.0	b137±27	65.3±27.3	34.1±27.5	0.03
Do	31.6	b133±19	61.9±21.1	37.5±21.3	(0.01-0.07)
Do	100.0	b104±25	31.5±24.9	68.2±25.1	-----
Hydrocortisone	0.316	b138±9	67.1±9.7	32.2±9.8	-----
Do	3.16	b109±21	36.9±21.8	62.8±21.9	1.0
Do	31.6	b79±8	7.2±8.7	92.7±8.8	-----

Positive control		171±18	98.6±18.7	-----	-----

* Calculated from negative control group average.

b Significantly ($P<0.05$) different from positive control.

Gallic acid and its alkyl esters are known compounds (Heilbron and Bunbury, Dictionary of Organic Compounds, 1953, Volume 2, page 583), and certain at least of these known compounds are known to have various pharmacological actions in mammals, including local anesthetic activity (Modak and Rao, Indian J. Med. Res., 1971, 59, 795-8), the boosting of the anti-Parkinsons disease activity of L-DOPA (German Offenlegungsschrift 2,103,284) and bronchodilating and decongestant activity (U.S. Patent Specification 3,639,622).

The invention provides a method of alleviating inflammation, edema and/or pain in a mammal by applying to the mammal by the topical route gallic acid or a C_{1-8} alkyl ester thereof, e.g. the methyl, the ethyl and particularly the propyl ester.

The method is particularly useful in the treatment of burns, for example those induced by ultra-violet radiation (i.e. sunburn).

The gallic acid or ester thereof can be administered in the form of a pharmaceutical composition comprising it and a pharmaceutically acceptable carrier or diluent. The composition is preferably in a form suitable for topical administration; examples are ointments, creams, pastes, liniments and jellies, as well as aerosol preparations.

50 These results are shown in graph form in the figure. Propyl gallate also has a significant antinociceptive effect in mice which indicates an analgesic effect in humans. The ability of arachidonic acid to induce abdominal constrictions (writhing) in mice was significantly ($P<0.01$) reduced after the arachidonic acid had been incubated at 37° C. for 25 min. with 100 μ g./ml. of propyl gallate. Similar results were obtained when the arachidonic acid was replaced without prior incubation by acetylcholine or acetic acid. Pretreatment of the mice with 4 mg./kg. of propyl gallate by the intraperitoneal route significantly ($P<0.05$) inhibited writhing induced by a subsequent intraperitoneal challenge with arachidonic acid; once again similar results were obtained when the arachidonic acid was replaced by acetylcholine or acetic acid. The method of Collier, Dinneen, Johnson and Schneider, Brit. J. Pharmacol., 1968, 32, 295-310, was used in these experiments. The results are summarized in Table 2.

55 Propyl gallate does not cause abdominal constrictions in mice at concentrations of 5 mg./ml. when injected intraperitoneally, indicating lack of irritancy when applied to the skin at these low concentrations.

60 Propyl gallate, and its homologues, are believed to act as free-radical scavengers, thus indicating effectiveness

in rapidly relieving pain and inflammation in humans. The speed of the local effectiveness of a compound is basically dependent on its absorption from the vehicle when applied to the site of inflammation.

TABLE 2
Inhibition by propyl gallate of abdominal constrictions (writhing) induced by arachidonic acid, acetylcholine or acetic acid in mice

Intraperitoneal treatment	No. of mice	No. of mice responding within—		
		0-30 sec.	0.5-2 min.	2-10 min.
AA plus control vehicle	40	4	10	22
AA plus progal (25 µg./ml.)†	35	2	5	**8
AA plus progal (100 µg./ml.)†	35	0	*1	**2
AA 5 min. after control vehicle	25	11	12	N.T. 15
AA 5 min. after progal (1 mg./kg.)	25	***1	*5	N.T.
AA 5 min. after progal (4 mg./kg.)	20	***0	*0	N.T.
ACh 5 min. after control vehicle	20	1	17	6/10
ACh 5 min. after progal (40 mg./kg.)	20	0	***2	*1/10 20
Acac 5 min. after control vehicle	40	0	1	19
Acac 5 min. after progal (10 mg./kg.)	30	0	0	**3

†0.25 and 1 mg./kg. respectively.

*P<0.05

**P<0.01.

***P<0.005.

NOTE.—N.T.=Not tested; AA=Arachidonic acid 1 mg./kg.; ACh=Acetylcholine bromide 3.2 mg. base/kg.; Acac=Acetic acid 75 mg./kg.; Progal=Propyl gallate dissolved in sodium phosphate buffer, 0.05M, pH 7.0; Dose volumes were 10 ml/kg. throughout.

We claim:

1. A method of treating inflammation or edema in a mammal, which method comprises:

topically administering to said mammal an effective amount of a compound selected from the group consisting of gallic acid and an alkyl ester of gallic acid, the alkyl moiety of said ester having 1 to 8 carbon atoms.

5 2. A method as claimed in claim 1 in which said alkyl ester is propyl gallate.

10 3. A method of treating inflammation associated with sunburn in a mammal, which method comprises:

topically administering to said mammal an effective amount of a compound selected from the group consisting of gallic acid and an alkyl ester of gallic acid, the alkyl moiety of said ester having 1 to 8 carbon atoms.

15 4. A method as claimed in claim 3 in which said alkyl ester is propyl gallate.
